UNITED STATES PATENT OFFICE

WILLIAM O. THOMPSON, OF PITTSBURGH, PENNSYLVANIA, ASSIGNOR TO STANDARD SANITARY MFG. CO., A CORPORATION OF PENNSYLVANIA

FLUSH-PIPE HOUSING

Application filed August 4, 1927. Serial No. 210,678.

This invention relates to plumbing fixtures and more particularly to flush pipe housings and means for securing the same in place.

Since porcelain bowls and porcelain tanks have come into use, it has been customary to cover the flush pipe which extends between the tank and bowl with a porcelain housing in order to improve the appearance of the combined apparatus.

These housings heretofore have been more or less loosely held in position and have been unsatisfactory on this account.

An object of this invention is to provide an improved porcelain housing for covering the flush pipe between the bowl and tank of a combined fixture and also to provide means for detachably but rigidly securing the housing in position.

This, as well as other objects which will readily appear to those skilled in this particular art, I attain by means of the housing and its attaching means described in the specification and illustrated in the accompanying drawings.

In the drawings, Figure 1 is a side view partially in elevation and partially in section of a fixture embodying this invention in place between a bowl and tank of a combined fixture. Figure 2 is a back view in elevation of the porcelain housing forming part of the invention. Fig. 3 is a top plan view of the device for detachably but rigidly securing the housing to the flush pipe and in place between the bowl and tank. Fig. 4 is a view taken on line 4—4 of Fig. 3 and Figs. 5 and 6 are detail views of a part of the attaching device and are taken 90° one from the other.

In the drawings, I have illustrated in a more or less general way a porcelain tank 7, a porcelain bowl 8, and a straight flush pipe 9 connecting the bowl and tank and secured in place by standard bowl fixtures 10 and standard tank fixtures 11.

In carrying out this invention, I preferably employ a porcelain housing 12 adapted to neatly fit in place between the tank and bowl and to hide the flush pipe and the tank and bowl fittings 10 and 11. The back of the upper portion of the housing is, so to speak, cut away as shown in Figs. 1 and 2 and a

notch 13 is provided at the center of the rear portion of the housing to accommodate the clamping means for securing the housing in place and to the flush pipe.

The clamping means comprises an annular member or ring 14 formed with a projecting stud 15 which is threaded to receive a wing nut 16. A clamping member having a cylindrical body portion 17 and a bifurcated inner end 18 is constructed to loosely slide on the threaded stud 15. The bifurcated end of the clamping member straddles ring 14 and the inner surfaces of its furcate parts are curved to conform to the surface of the flush pipe.

A spring member 19 pierced to receive stud 15 is positioned between the outer end of the clamping member and the wing nut. This spring member is more or less rectangular and is bent so as to provide contact feet 20 at its opposite ends which are adapted to contact with the housing on opposite sides of notch 13.

When the housing is in position with notch 13 directly behind the flush pipe with ring 14 in position on the fixture and with the cylindrical portion 17 of the clamping member lying within notch 13 of the housing the housing may be clamped in position by tightening the wing nut. By tightening the wing nut the curved inner ends of the furcate parts 18 are forced into engagement with the flush pipe and the front of the ring is forced rearwardly in tight contact with the front of the flush pipe. In other words the pipe is securely gripped by the clamping device. As the wing nut is screwed home it carries with it the spring 19 and forces its feet 20 into firm contact with the back of the housing on opposite sides of the notch 13. In this way the housing is rigidly attached to the flush pipe and is held in fixed position between the tank and bowl.

In assembling the device the housing 12 and the clamping means is placed in position about the pipe. The pipe is then connected to the tank 7 and bowl 8 by the standard fixtures 10 and 11. The cutaway portion of the back part of the housing 12 is rotated to the front giving access to the connection 11 and after the connection 11 has been made, the housing is rotated about the pipe 11 to posi-

tion the cutaway portion in the rear of the fixture to prevent its observation. The clamping means is then operated to render the housing in rigid fixed relation with the flush pipe as stated above.

5 Accordingly I have provided a sanitary fixture comprising a tank and a bowl, a flush pipe connection therebetween, a housing for the flush pipe and means for rigidly fastening the housing to the pipe and maintaining the housing in a predetermined spaced relation to the pipe.

10 While I have illustrated and described but one embodiment of this invention it will be apparent to those skilled in the art that certain changes, modifications, substitutions, additions and omissions may be made in the housing and its attaching means without departing from the spirit and scope of the ap- 15 pended claims.

15 What I claim as new and desire to secure by Letters Patent is:

1. A sanitary fixture comprising a flush pipe, a housing therefor and means for rigidly fastening the said housing in fixed relation to the pipe, the said means comprising an encircling member, a grooved member fitting against the pipe cooperating with the encircling member and locking said member to the 20 housing.

2. In a sanitary fixture and in combination with a flush pipe, a housing for the pipe and means for holding the housing in position with relation to said pipe, said means comprising a cylindrical portion for encircling the pipe, an adjustable clamp secured to said cylindrical portion, a spring fitting the outer surface of the housing and cooperating with the clamping device.

3. A sanitary fixture comprising a flush pipe, a housing for said pipe, a spring member engaging said housing and a clamping device adapted to cooperate with the spring member for maintaining the housing in rigid fixed relation to the pipe; said clamping device being independent of the housing, and having a member encircling said pipe.

4. In a sanitary fixture, the combination with a flush pipe, of a housing for the pipe having an opening therein for giving access to the pipe provided with means adapted to receive a locking device, a spring engaging the outer surface of the housing, a clamping device for locking said spring to the housing and rigidly securing the housing in fixed relation to the pipe.

5. A sanitary fixture comprising a flush pipe, a housing therefor and means for rigidly fixing the housing to the pipe, the said means comprising a cylindrical member having a threaded stud thereon, a cooperating member having a cylindrical opening and a groove therein for engaging and cooperating with the stud and cylindrical member, a spring 65 washer and a clamping member for the stud.

6. A sanitary fixture comprising a flush pipe, a housing therefor and means for fastening the housing to the said pipe, the said means comprising a continuous annular member for engaging the outer surface of the pipe having a threaded stud disposed thereon, a connecting member having a cylindrical opening therethrough and a slot for receiving the threaded stud and annular member respectively, a spring washer for the stud having projections for engaging the housing and a clamping nut for the threaded stud for actuating the connecting member and spring washer.

7. A sanitary fixture comprising a flush pipe, a housing therefor, means for positively maintaining the housing in spaced relation to the pipe, the said means comprising a cylindrical member for engaging the pipe having a threaded stud thereon, a cooperating member for the stud and the cylindrical member adapted to lie within the housing and a clamping member for the stud.

In testimony whereof, I have hereunto subscribed my name this 22nd day of July, 1927.

WILLIAM O. THOMPSON.
